F. L. FISHER

BOOKBINDER

Filed Dec. 8, 1923

INVENTOR

F.L.Fisher.

BY
Charles P. Griffin
ATTORNEY.

UNITED STATES PATENT OFFICE.

FRANCIS L. FISHER, OF SAN FRANCISCO, CALIFORNIA, ASSIGNOR OF ONE-HALF TO
WILLIAM H. SMITH, OF SAN FRANCISCO, CALIFORNIA.

BOOKBINDER.

Application filed December 8, 1923. Serial No. 679,368.

To all whom it may concern:

Be it known that I, FRANCIS L. FISHER, a citizen of the United States, residing at San Francisco, in the county of San Francisco, State of California, have invented a new and useful Bookbinder, of which the following is a specification, in such full and clear terms as will enable those skilled in the art to construct and use the same.

10 This invention relates to a book binder intended to provide a binding for loose leaf books which is capable of being subsequently made into a permanently bound book when the desired number of leaves has been 15 assembled therein.

It will be understood by those skilled in the art that during the course of a month or several months, there may be an accumulation in a loose leaf book of a series of 20 invoices or bills or ledger leaves, which leaves are removed from time to time for changing or for having certain matter added thereto, but which leaves, after a certain period of time, are bound up in the 25 book in a permanent form. This book is intended to provide for both contingencies, that is, it is used in the first instance, for the binding of the loose-leaf-incompleted book. When the desired number of leaves 30 has been placed in position, the covers and leaves are made into a permanent book from which the leaves cannot be easily removed unless they are torn out, the binding posts being then bent down as shown in dotted 35 lines in Fig. 1.

Another object of the invention is to provide a binding post for the book which will be stiff enough to hold its proper position in the simplest possible manner.

40 Another object of the invention is to produce a binding post which will be very stiff in one plane, but very easily bent over in a plane at right angles thereto when it is desired to produce a permanent book.

45 Another object of the invention is to provide the book binding with means for concealing the bent over ends of the post thereby producing a neat binding with no rough edges projecting.

50 A further object of the invention is to provide a lock for securing the binding in the locked position, said lock being capable of being made stiff enough to be substan-

tially permanent when once inserted in place, if that is desired.

55 Other objects of the invention will appear as the description proceeds.

An embodiment of the invention is shown in the accompanying drawings in which the same reference numeral is applied to the 60 same portion throughout, but I am aware that there may be modifications thereof.

Fig. 1 is a perspective view of the completely bound permanent book,

Fig. 2 is an end view of the lower cover 65 of the book,

Fig. 3 is an edge elevation of the lower cover of the book looking at right angles to Fig. 2,

Fig. 4 is an edge elevation of the lower 70 cover and the upper cover of the book, no leaves being shown in place, a portion of the cover and back being shown in section for purpose of illustration, this figure illustrating the way the book temporarily appears during the time the leaves may be inserted therein or removed therefrom.

Fig. 5 is an edge view of the back end of the upper cover of the book showing the binding post ready to be turned down,

80 Fig. 6 is an edge view of a portion of the upper cover of the book showing the binding post turned down and the cover in the proper position for protecting the book leaves,

85 Fig. 7 is a plan view of a portion of the back of the book binding showing the manner of securing the binding post thereto,

Fig. 8 is a plan view of a portion of the upper cover of the book showing the binding post turned down preparatory to locking the back edges of the upper cover together,

Fig. 9 is a side elevation, and

Fig. 10 is a plan view of the locking member for securing the two back edges of the cover together.

95 Fig. 11 is a perspective view of the locking device which may be applied to the loose cover to prevent it from dropping off the 103 binding posts.

The two covers consist of the ordinary binder's-board material 1 and 2 which may be covered with cloth or paper, as may seem desirable, and these binder's board backs 105 are connected one to a single and one to a

pair of metal strips 3, 4 and 5 with edges 5 inturned to form slotted-tubular members by suitable cloth strips 6 and 7, or by leather hinge material, if desired, which 10 completely covers said metal elements and which is glued to the edges of binder's board covers 1 and 2.

The metal strips are all made substantially alike and consist of a flat piece of 10 metal 8 with the inturned edges 9 spaced from each other and spaced from the middle of the strip far enough to leave room to insert a prong of the sheet-metal lock 10. This lock has a short prong 11 and a long 15 prong 12 to facilitate its insertion into the two strips 4 and 5 of the upper cover. The prongs of the lock 14 have crimped portions as indicated at 13 which may be arranged to fit so tightly into the end of the 20 metal strip as to substantially prevent its removal, or it may be flat as to allow it to be removed at will.

The lock has a knob 14, which may be made of a suitable material to prevent it 25 from injuring desks or furniture, the metal strips being short enough to allow said knob to come in alignment with each edge of the cover 2, as illustrated at 16, Fig. 1.

It will be seen that the upper cover has 30 two of the metal strips 4 and 5 connected thereto and that they are hinged together at 17 and are hinged to the cover at 18, the construction of said metal strips being such that when the cloth cover is put on there 35 will be a groove in each strip as shown at 19 and 20, in Fig. 8, the object being to allow the posts 21 and 22 to be locked in place, as shown in Fig. 8, by being hammered down into the groove produced in 40 said metal strips and not increase the thickness of the same.

The posts 21, 22 consist of doubled lengths of wire the ends of which, as shown at 23, 45 24, are bent at right angles to the two wires in such a manner as to stand substantially parallel to each other, but adapted to be inserted at an angle of forty-five degrees to the length of the metal strip to which they are secured the object being to hold 50 said posts as stiffly as may be.

In use a series of loose-leaves, such as bills or invoices are assembled in the book, when it is in the condition illustrated in Fig. 4, and as long as it is desired to add 55 leaves to or remove leaves from the book, the posts 21, 22 are allowed to remain in that condition. However, when all of the leaves have been assembled in the book, that it is desired to place there, the top 60 cover is then turned back with the member 5 free from the posts 21, 22 as shown in Fig. 5, whereupon the two posts 21 and 22 are hammered down tightly on the member 4 to the position illustrated in Fig. 8. 65 The cover of the book is then turned over

to the position shown in Fig. 6, whereupon one of the locks 10 may be inserted in each end of the two strips 4 and 5 to hold the book permanently in the shape shown in Fig. 1. It will be seen from the above that 70 the posts 21, 22 for holding the leaves pass through holes in both of the strips 4 and 5 when the book is used merely as a loose leaf book, as for example, when leaves are being put in from day to day, but that 75 when the book is full that the member 5 is removed from the posts and the posts then pass through only the member 4 and the book is changed to a permanent form by having the posts bent down, 80 whereupon the cover 2 may be closed in the usual manner.

In Fig. 11 there is shown a form of locking device which is intended to secure a loose cover in place while the book is being 85 used as a detachable loose leaf book. In this figure the numeral 30 indicates the book cover, 31 the hinged portion of the book cover through which the binding posts pass, 32 indicates one of the binding posts, 90 and the locking device consists of a curved wire 34 pivoted to the hinged member 31 at 34'. This allows the locking device to rotate in the plane of the binder cover and its pointed end 38 is adapted to pass between the two wires of the binding post spreading them apart to prevent the cover from 95 slipping off of them.

What I claim is as follows, but modifications may be made in carrying out the invention shown in the drawings and in the above particularly described form thereof, within the purview of the invention, as defined by the annexed claims.

1. In a book binder, the combination of 105 a back, of posts secured thereto, a cover having two perforated strips hinged in series thereto at one edge through one or both of which the posts may be passed, and means to secure said strips together when the book 110 is to be made permanent.

2. A binder for books, comprising a back having a strip hinged thereto at one edge, a post consisting of a doubled wire with its ends extending into said strip and lying 115 at an acute angle of the length thereof, a cover, two strips hinged in series to the cover each of which is perforated to receive said post and means to secure said strips together when the post has been bent down over one of the strips.

3. In a book binder, the combination with 125 a back, of a strip hinged thereto, posts carried by said strip, a cover, a pair of perforated strips hinged in series to the cover, said posts being adapted to pass through one or both of said strips, and means at the end of the strips to secure them together one overlying the other.

4. In a binder for books, the combination 130

with a back, of a hinged strip secured thereto, posts carried by said strip, a cover, two hinged strips connected in series with said cover and a friction lock to clamp the latter 5 strips together at the ends thereof.

5. In a binder for books, the combination with a back of a hinged strip secured thereto, posts carried by said strip, a cover, a pair of perforated strips hinged together 10 and to the cover, said posts being adapted to pass through one or both of the latter strips and a spring lock at each end of the latter two strips to secure them together one overlying the other.

15 6. In a book binder, the combination with a back of a hinged strip secured thereto, posts carried by said strip, a cover, a pair of perforated strips hinged to each other and to the cover, said posts being adapted 20 to pass through one or both of the latter strips, and means extending into the latter strips at their ends to secure them together one overlying the other.

7. In a book binder, the combination with 25 a back of a strip hinged thereto, posts carried by said strips, a cover, a pair of perforated strips connected to each other and to the cover said cover being adapted to pass through one or both of said strips and 30 a forked clamp at the end of said strips to secure them together one overlying the other.

8. In a book binder, the combination with

a back of a hinged strip secured thereto, posts carried by said hinged strip, a cover, a pair of perforated hinged strips connected 35 in series to the cover said posts being adapted to pass through one or both of said strips and means on the outside of the cover to prevent the cover from becoming disconnected from the posts.

40 9. In a book binder, the combination with a back of a hinged strip secured thereto, posts carried by said strip to secure a plurality of leaves to the back, a cover, a pair of perforated strips hinged to each other 45 and to the cover and adapted to be threaded on to said posts, means thereon to engage said posts to prevent the cover from falling off said posts.

45 10. In a book binder, the combination with a back of a hinged strip connected therewith, posts carried by said strip to secure a plurality of leaves to the back, a cover, a pair of perforated tubular strips 50 secured to each other and to the cover through which said posts may pass and means adapted to extend into each of said strips at their ends to secure them together one overlying the other.

55 In testimony whereof I have hereunto set 60 my hand this 28th day of November A. D. 1923.

FRANCIS L. FISHER.
